EASEL

Douglas L. Cole, 6032 50th St. NE., Seattle, Wash.

Filed Jan. 23, 1964, Ser. No. 78,331

Term of patent 14 years

(Cl. D29—20)

FIG. 1

FIGURE 1 is a top perspective view of an easel showing my new design;

FIGURE 2 is a front-elevational view of the easel; and,
FIGURE 3 is a side-elevational view of the easel.

I claim:

The ornamental design for an easel, substantially as shown.
